UNITED STATES PATENT OFFICE

2,516,110

DEVICE FOR APPLYING LIQUID ADHESIVE
TO WORKPIECESHarry D. Elliott, Wenham, Mass., assignor to
United Shoe Machinery Corporation, Flemington, N. J., a corporation of New Jersey

Application July 25, 1947, Serial No. 763,561

4 Claims. (Cl. 91—47)

1

This invention relates to devices for applying liquid adhesive to work pieces such as strips of tape for reinforcing shoe parts. The device illustrated herein can conveniently be incorporated in a reinforcing-tape-applying machine of the type disclosed in United States Letters Patent No. 2,453,212, granted on November 9, 1948, upon an application filed in my name and of which the present application is a continuation-in-part.

The adhesive commonly used in such machines is solid at room temperatures and is maintained in workable fluid condition by heating units such as electrical resistance coils. The illustrated device comprises an applicator which is raised from beneath the surface of a liquid adhesive contained in a receptacle into contact with the under surface of a work piece supported above the liquid adhesive and it includes also a pump for supplying liquid adhesive to the receptacle. Inasmuch as the applicator and the movable element of the pump must perform their movements in contact with the adhesive, it is evident that the operation of these movable members is dependent upon the fluidity of the adhesive and that, in the absence of some provision to the contrary, a congealing of the adhesive during operation of the device or an attempt to start the operation of the device after the adhesive has congealed might result in breakage of the movable members or their operating mechanism.

It is an object of the present invention to provide an adhesive applying device which is not subject to breakage by reason of attempted operation while the adhesive is in a congealed state. In accordance with a feature of the invention, the illustrated device includes, in its mechanism for operating the applicator and the pump, an element which can yield to avoid breakage when movement of any part of the device is prevented by the congealed adhesive. As shown herein, the operating mechanism of the device includes a lever composed of two arms normally held in predetermined angular relation by a spring, one of the arms carrying a cam roll which is held in contact with its operating cam by another spring. Rotation of the cam can take place when the liquid is congealed, in which case either the first mentioned spring will yield to enable the cam roll to be moved radially outward by the cam or the second mentioned spring will remain stretched to enable the cam roll to remain off the periphery of the depressed portion of the cam.

These and other features of the invention, including various details of construction and combinations of parts, will be more particularly de-

2

scribed by reference to the accompanying drawings and pointed out in the claims.

In the drawings,

Fig. 1 is a plan view of an illustrative machine embodying the invention;

Fig. 2 is a vertical section of the machine taken on the line II—II of Fig. 1;

Fig. 3 is a vertical section taken on the line III—III of Fig. 1; and

Fig. 4 is a vertical section taken on the line IV—IV of Fig. 1.

Many of the parts of the machine herein illustrated are similar to parts of the machine disclosed in Letters Patent No. 2,453,212, above mentioned, and are identified herein, for convenience, by the same reference characters as are used to identify corresponding parts in said Letters Patent.

The tape engaging instrumentalities of the illustrated machine include an upper feed roll 10 (Fig. 3) and a lower feed roll 12 cooperating therewith to feed a predetermined length of tape T transversely of the machine, a horizontal wire 14 for supporting the tape thus fed above a receptacle 16 which contains a liquid adhesive, an applicator 18 (Fig. 2) for raising a quantity of adhesive from the receptacle and applying it to the under surface of the supported tape, and a pair of cutting blades 20 and 22 for severing the length of tape. The machine is further provided with a work table 24 for supporting a shoe part (not shown) to which the adhesively coated and severed length of tape is moved by a transfer mechanism 26 from its position on the wire 14 to a forward position on the shoe part. The tape in its passage to the feed rolls 10 and 12 is drawn from a reel and through a guide, neither of which is shown herein.

The supporting structure of the machine comprises a rigid housing 36 adapted to be secured upon a work bench. A cover 48 (Fig. 1) is provided for such portions of the driving mechanism as would otherwise be exposed.

The feed rolls 10 and 12, the transfer mechanism 26, and the applicator 18 are all driven by mechanism operated by a countershaft 82 (Fig. 1) which is driven through a gear 84 and a pinion 86 from a drive shaft 88. An automatically disengaging clutch 90, including a cam 92, couples a pulley 94 to the drive shaft 88 to cause the machine to be driven through a single cycle of operations. The pulley 94 is driven through a belt 96 from a pulley 98 mounted upon the shaft of a motor 100.

The receptacle 16 is supported upon a heated

block 108 (Fig. 3) mounted within the housing 36 and is supplied with a thermoactive adhesive, liquid when hot and solid when cold, from a container 110 by means which will be described later. The tape supporting wire 14 is secured to the receptacle 16 by screws 112. The applicator 18 comprises a bar extending lengthwise of the container (i. e., transversely of the machine) and having a horizontal top edge 114 (Fig. 1) which, when the applicator is raised out of the adhesive within the receptacle 16, comes into contact with the under surface of the supported tape and thus applies adhesive to the tape while the tape is held down on the wire 14 by the transfer device 26. The applicator 18 is integral with a bracket 116 which, in plan view (Fig. 1), is rectangular with a rectangular central opening 117, and which, in side elevation (Fig. 2), is seen to bend down below the surface of the liquid adhesive in the receptacle 16, then forward, and then up to the ends of the applicator 18 which constitutes the forward portion of the bracket 116. The bracket 116 has a rearwardly extending shank 118 by which it is mounted upon a lever 120. A pair of screws 122, extending through slots in the shank 118 which permit forward and rearward adjustment, secure the shank 118 to the lever 120. A stop screw 124 (Figs. 1 and 3), threaded downwardly through a lug 126 extending from a stationary portion of the machine, engages the shank 118 to limit the upward movement of the applicator. The lever 120 has a hub 128 (Fig. 1) by which the lever is pivotally mounted upon a stationary shaft 130. A post 132 (Fig. 2) rising from the base plate of the housing 36 supports one end of the shaft 130, and a boss 134 on the right-hand side wall of the housing supports the other end of the shaft. The shaft 130 is also utilized to support the housing 48.

The mechanism for operating the applicator 18 comprises a lever 136 having a hub 138 which is freely rotatable upon the shaft 130. Carried upon the free end of the lever 136 is a cam roll 140 engageable with a cam 142 secured upon the countershaft 82. A spring 144 secured at its upper end to the lever 136, and anchored at its lower end to a hook 146 secured in the housing 36, normally holds the roll 140 in engagement with the cam. Formed upon the lever 136 is a lug 148 engageable with a lug 150 extending laterally from the lever 120. A tension spring 152 connected at its ends to the levers 120 and 136, respectively, normally holds the lugs 148 and 150 in engagement with each other. The construction just described serves to prevent danger of breakage when the adhesive, liquid only while hot, is congealed in the receptacle 16. For example, if the applicator 18, while in its lowermost position as shown in Fig. 2, is embedded in a mass of congealed liquid, the rotation of the cam 142 will bring the low portion of the cam beneath the roll 140, but will not cause breakage because the spring 144 will exert its force yieldingly upon the lever 136 without bringing the cam roll into engagement with the low portion of the cam. If, on the other hand, the applicator 18 should be in its uppermost position above a mass of congealed adhesive, the rotation of the cam 142, while positively forcing the lever 136 up, will not forcibly move the lever 120 because the spring 152 will yield and permit the lugs 148 and 150 to separate.

The various parts of the illustrated machine, as so far described, are similar in construction and mode of operation to like numbered parts

of the machine disclosed in Letters Patent No. 2,453, 212, above mentioned.

The machine shown herein is further provided with means, now to be described, for maintaining a supply of liquid adhesive at a constant level within the receptacle 16. The container 110 from which the adhesive is supplied comprises a reservoir 500 which receives the adhesive from an inverted carton 502 mounted directly above it and supported upon a wire 504 extending diametrically across the reservoir 500. A cover 506 fits over the carton 502 when the latter is thus positioned over the reservoir 500. The adhesive, which is initially solid in the carton 502, is melted by a heating device, later to be described, and drops into the reservoir 500 wherein it is maintained in liquid condition. The carton 502 may conveniently be the same pasteboard container in which the adhesive is purchased.

The receptacle 16 and the reservoir 500 are integral, being parts of a single casting, and they are joined by a neck which is channel shaped in cross section and which has a pair of side walls 508 (Figs. 1 and 3) and a thick base 510 (Fig. 3) having its upper surface above the highest level to which liquid adhesive will be supplied to the reservoir 500. This neck extends from a lug 512 formed on the side of the reservoir 500. The channel formed by the walls 508 and the base 510 communicates at one end with the interior of the receptacle 16 and at its opposite end with the interior of the reservoir 500. It thus serves as a passageway for excess liquid adhesive in the receptacle 16 to flow back into the reservoir 500.

Extending heightwise through the lug 512 is a bore 514 (Figs. 2 and 4) which serves as a cylinder for a pump plunger 516. Disposed horizontally in the lug 512 and providing communication between the bore 514 and the interior of the reservoir 500 is a bore 518 which serves as an inlet duct to the pump. Extending down into the lug 512 parallel to the bore 514 is a bore 520 which serves as a valve chamber. Continuing down through the lug 512 is a bore 522 coaxial with the bore 520 and of smaller diameter, leaving a shoulder at the junction of the bores 522 and 520 which forms a seat for a ball valve 526. Formed in the under surface of the lug 512 and connecting the lower ends of the bores 514 and 522 is a groove 528. A cover plate 530 secured to the under surface of the lug 512 covers the groove 528 to form a duct leading from the bore or pump cylinder 514 to the bore 522 or valve entrance. The plate 530 covers also the lower ends of the bores 514 and 522. The pump inlet duct 518 enters the pump cylinder 514 at a level slightly higher than the level at which the groove 528, which is the pump outlet duct, leaves the pump cylinder.

Extending horizontally lengthwise through the thick base 510 of the neck 508 is a duct 532 communicating with the upper portion of the valve chamber 520 and constituting the valve outlet duct. Leading up from the duct 532 and opening into the interior of the receptacle 16 is an inclined passage 534 which is a continuation of the duct 532.

The pump plunger 516 has an integral upwardly extending stem 536 (Fig. 2), the upper end of which carries a pair of rotatable horizontal coaxial pins 538 (Fig. 1). The outer end portions of these pins 538 are in the form of slide blocks which engage slots provided in a pair of ears extending from a crank arm 540 which is mounted

upon one end portion of a shaft 542. The opposite end portion of the shaft 542 carries a gear segment 544 (Fig. 2) which meshes with and is driven by a gear segment 546 on the lever 120. The shaft 542 is journaled in a bearing 548 (Fig. 3) which is integral with a cover 550 secured upon the upper edge of the casting which forms the receptacle 16 and the reservoir 500. The lug 126, previously mentioned, is integral with the bearing 548. The cover 550 covers the passageway formed by the side walls 508 and the base 510, and it also has a ring shaped portion extending over the reservoir 500 for receiving the carton 502 and supporting the cover 506. A groove 552 formed in the upper surface of the lug 512 connects the upper portion of the pump cylinder 514 with the passage between the walls 508 to permit the escape of air from the pump cylinder as the plunger 516 rises. The cover 550 covers the groove 552 and the top of the pump cylinder 514, having a bearing hole through which the stem 536 reciprocates.

The level of the liquid adhesive within the receptacle 16 is determined by an overflow weir 554 extending across the passageway between the walls 508. The weir 554 consists of a bent up edge portion of a plate 556 which is secured upon the base 510, the top edge of the weir being within the reservoir 500 to enable surplus adhesive from the receptacle 16 to drip down into the mass of adhesive within the reservoir. The plate 556 serves also to close the upper end of the valve chamber 520.

The adhesive within the receptacle is maintained in a fluid state by an electrical resistance heating unit 558 which fits within a horizontal bore in the block 108. The adhesive within the reservoir is maintained in a liquid state, and the solid adhesive within the carton 502 is melted, by an electrical resistance heating unit 560 which fits within heightwise coaxial bores in the cover 550 and the lug 512. An opening 562 in the cover 550 directly over the weir 554 enables the operator to observe conditions within the reservoir 500. A guard 564 secured to the reservoir 500 and spaced therefrom protects the operator's hands from accidental contact with the heated reservoir.

The operation of the above described instrumentalities for supplying adhesive from the reservoir 500 to the receptacle 16 is effected by movements of the lever 120 acting, through the gear segments 546 and 544, the shaft 542, and the crank arm 540, to reciprocate the plunger 516 in unison with the applicator 18. Upward movement of the plunger 516 effects a partial vacuum in the pump cylinder 514 below the plunger and also in the groove 528 and the bore 522 which holds the valve 526 upon its seat. As soon as the plunger rises high enough to uncover the opening of the inlet duct 518, liquid adhesive flows from this duct into the pump cylinder to relieve this vacuum. Descent of the plunger 516 first closes the opening of the duct 518 and prevents the liquid in the pump cylinder from escaping back through the duct 518 into the reservoir 500, and continued descent of the plunger forces the liquid trapped in the pump cylinder, the groove 528, and the bore 522 up past the valve 526 into the valve chamber 520 and thence through the duct 532 and the passage 534 into the receptacle 16.

The diameter of the pump cylinder 514 and the length of the stroke of the plunger 516 are both slight and the quantity of adhesive delivered by each stroke of the pump is not more than a few

drops. Although the plunger 516 in its upward movement is working to some extent against atmospheric pressure, the force required to raise it is not great enough to overcome the tension of the spring 144. The quantity of adhesive applied to the tape T with each upward stroke of the applicator 18 is slightly less than the quantity delivered to the receptacle 16 with each downward stroke of the plunger 516, and the excess flows over the weir 554 into the reservoir 500.

If for any reason the heating system should fail during operation and the adhesive should congeal, or if rotation of the shaft 82 should inadvertently be started before the adhesive has melted, no breakage will take place by reason of the plunger 516 being held stationary by the congealed adhesive. In such case the spring 152 would yield without forcing the plunger down, and the spring 144 would remain stretched without forcing the plunger up. These springs thus serve as yielding elements in the plunger operating means as well as in the applicator operating means.

Having described my invention, what I claim as new and desire to secure by Letters Patent of the United States is:

1. In a device for applying a congealable liquid adhesive to a work piece, a receptacle for said liquid adhesive, means movable through said liquid adhesive for applying the liquid adhesive to the work piece, a pump for supplying liquid adhesive to the receptacle, a common means for operating said applying means and said pump, adjacent members having abutting surfaces and included in said common operating means, and a spring normally holding said surfaces together to render the members effective to transmit movement from one to the other, said spring being yieldable in response to excessive resistance offered by the adhesive to the operation of the applying means and the pump, said spring serving thereby to avoid breakage by reason of a congealing of the liquid adhesive.

2. In a device for applying a congealable liquid adhesive to a work piece, a receptacle for said liquid adhesive, said receptacle having an overflow weir, a pump for supplying liquid adhesive to said receptacle to maintain the surface of the liquid adhesive in the receptacle at a constant level determined by said overflow weir, an applicator adapted to be raised from below the surface of the liquid adhesive in the receptacle into contact with a work piece above said surface to cause the applicator to apply some of the liquid adhesive to the work piece, a common means for operating said pump and said applicator, a pair of movement-transmitting members being included in said common operating means, said movement-transmitting members being mounted for movement in overlapping paths and having abutting surfaces, and a spring normally holding said surfaces in contact to render the members effective to operate the pump and the applicator, said spring being yieldable in response to excessive resistance offered by the adhesive to the operation of the applicator and the pump, said spring serving thereby to avoid breakage by reason of a congealing of the liquid adhesive.

3. In a device for applying a congealable liquid adhesive to a work piece, a receptacle for said liquid adhesive, an applicator adapted to be raised from below the surface of the liquid adhesive in the receptacle into contact with a work piece above said surface to cause the applicator to apply some of the liquid adhesive to the work

piece, a reciprocating pump having a plunger movable heightwise in a cylinder for supplying liquid adhesive to said receptacle, a common operating member connected to said applicator and said plunger, and means for raising and lowering said operating member to operate the applicator and the pump in unison.

4. In a device for applying a congealable liquid adhesive to a work piece, a receptacle for said liquid adhesive, means for supporting the work piece above the liquid adhesive in said receptacle, an applicator adapted to be raised from below the surface of the liquid adhesive in the receptacle into contact with the under surface of the work piece to apply some of the liquid adhesive to the work piece, a lever upon which said applicator is mounted, a fulcrum about which said lever swings to effect heightwise movement of the applicator, a second lever pivotally mounted on said fulcrum mutually engageable stops on said levers through which the second lever can positively swing the first lever about said fulcrum in one direction, a spring having its ends secured respectively to the levers and through which the second lever can yieldably swing the first lever about said fulcrum in the opposite direction, a movable cam, a cam follower on the

5
10
15

second lever engageable with said cam, said cam being arranged to swing the second lever and thereby the first lever in the second-mentioned direction, and a spring acting yieldingly upon the second lever and thence, through the stops, upon the first lever to swing the first lever in the first-mentioned direction against the cam, the purpose of the first spring being to prevent breakage which might result from the positive thrust of the cam against the cam follower when the adhesive is congealed, and the purpose of the second spring being to hold the cam follower yieldably against the cam and thereby to prevent breakage when the adhesive is congealed.

HARRY D. ELLIOTT.
